[57] CLAIM

The ornamental design for an automobile body, as
shown and described.

DESCRIPTION

FIG. 1 is a top plan view of an automobile body showing
my new design;

FIG. 2 is a front elevation view thereof;

FIG. 3 is a rear elevation view thereof;

FIG. 4 is a side elevation view thereof, the opposite side
being a mirror image of that shown;

FIG. 5 is a front perspective view thereof;

FIG. 6 is a rear perspective view thereof.
